(57) **CLAIM**

The ornamental design for a dental abutment sealing plug, as shown and described.

DESCRIPTION

FIG. 1 is a top perspective view of a dental abutment seal plug showing our new design;

FIG. 2 is a front view thereof,

FIG. 3 is a top plan view thereof

FIG. 4 is a bottom plan view thereof;

FIG. 5 is a top perspective view of a dental abutment seal plug showing a second embodiment;

FIG. 6 is a front view thereof,

FIG. 7 is a top plan view thereof

FIG. 8 is a bottom plan view thereof;

FIG. 9 is a top perspective view of a dental abutment seal plug showing a third embodiment;

FIG. 10 is a front view thereof,

FIG. 11 is a top plan view thereof; and,

FIG. 12 is a bottom plan view thereof.

The broken lines illustrate portions of the dental abutment sealing plug that form no part of the claimed design. The dental abutment sealing plug is shown with two symbolic breaks in its length in FIGS. 1, 2, 5, 6, 9 and 10. The appearance of any portion of the dental abutment sealing plug not shown between the break lines forms no part of the claimed design.
